James St. Willard
Sellers Patent

The Schedule referred to in these Sellers Patent and making part of the ^{same} containing a description in the words of the said James St. Willard himself of his improvement in the apparatus for setting the bones of fractured limbs.

It is known that James St. Willard of Brownhelm in the County of Lorain and State of Ohio have invented a new and useful improvement being an apparatus for setting the bones of fractured limbs which invention is described as follows reference being had to the accompanying draught. The apparatus consists of a board A of suitable length and breadth having two grooves D. D. running the entire length of the board A for the reception of slides and a joint near the centre. At A. A slide B. with two erect standards C. C. having a groove in each through which passing metallic screws attached at their lower extremity to a cross bar B. with thumb nuts E. E. resting upon the upper extremity of the groove piece C. C. at the bottom of slide B. is a thumb screw D. 8nd. A slide Q. with a roller R. a cog wheel S. a dog T. and a crank U. 3rd. A slide V. constituting oblique standards K. K. this flat cross bar L. L. the lower one having two perforations and there is a roller M. at the top of the standards K. K. with a slide W. called a scutch. At the upper end of board A. and on the under side is attached a broad stripe of webbin X. which passes over the cross bar B. in the slide B. and is attached to the roller R. in slide Q. At the lower extremity of A. is a pulley N. At the upper end of the board on both sides are two staples O. O. through which passes a strap P. Y. thin broad splint. In the application of this apparatus it is to be used on green groynes. In the first place the gravitation of the body is kept from the apparatus thereby preventing

ing the necessity of any counter extending force. In the second place the flexor and extensor muscles are balanced or antagonized by keeping the limb in a flexed or bent position. In the third place the extension is made directly in the axis of the broken bones the apparatus common as the whole limb. It supersedes the necessity of tight-lacing, and prevents all evasions from unequal pressure. It admits of the limb being dressed without a possibility of moving or misplacing the bones. which makes it of great importance in all compound fractures. It prevents the contraction of the muscles and consequent misplacing of the bones by keeping a gradual passive extension thereby procuring the greatest possible degree of safety and convenience. The apparatus places the limb in a situation most favorable for a free circulation of air around it in every direction. To apply the apparatus in case of fractured femur. a bandage called a roll is should be attached to the webbing at its upper extremity. The right bar to slide B. should be brought by means of the slide to such a point of elevation as the length of limb requires. The slide C should then be placed at such a distance from the knee as to permit the heel to just drop over the roller D. The webbing should now be made tight. The slide B must be placed a little short of the length of the sound thigh. The slide V should be placed in that groove which will correspond with with the inside of the fractured thigh brought down to the slide B and then left. The operator will then tie a bandage over or felt above the condiles of the knee, and give the limb into the hands of an assistant in a flexed position. another assistant will slide the apparatus under the limb and wrap and tie up till the upper extremity of the apparatus rests firmly upon the tuberosity of the Ischium. The outlet or slide V should now be brought up on the grain and firmly, pressed against the pubis and secured by the pins. In the limb should then be placed

placed upon the scabbing) taking care that the hollow of the hand rests directly over the cross bar B. The limb will now be fastened to the cross bar by means of the strap or fillet. Such extension should then be made as is necessary to bring the bone in proper position and the slide C. fastened by the thumb screws. An assistant will now be directed to clasp the limb with both hands and draw the muscles from above downwards as in the manner of dressing a stump after amputation. While the operator brings the bandage after his hands till he comes to the knee including the scabbing, when he should turn the bandage once or twice over the bone and under the cross bar in the form of a figure 8 then apply the splint X on the top of the thigh and carry his collar back to the starting place. Additional extensions can be made at discretion by attaching the end of pulley N. to the projecting extremity of splint X. and letting it run over the pulley N. in slide U. What I claim as my invention and which I desire to secure by letters Patent consists in the apparatus for setting and securing the bones of fractured limbs as before specified and described.
